UNITED STATES PATENT OFFICE.

WILLIAM CUTTER FORCE, OF NORTH PLAINFIELD, NEW JERSEY.

TESTING DEVICE FOR GAS-ENGINES.

1,095,273.

Specification of Letters Patent.

Patented May 5, 1914.

Application filed April 28, 1913. Serial No. 763,993.

To all whom it may concern:

Be it known that I, WILLIAM C. FORCE, a citizen of the United States, and a resident of North Plainfield, in the county of Somerset and State of New Jersey, have invented certain new and useful Improvements in Testing Devices for Gas-Engines, of which the following is a specification.

The present invention relates generally to 10 a testing device for an internal combustion motor, and has for its object the production of a device for conveniently and quickly testing the ignition system of the motor, and locating misfiring in cylinders.

15 The invention consists of the features expressed in the claims, a preferred embodiment of which is shown in the accompanying drawings and description.

In the said drawings: Figure 1 is a dia- 20 grammatic view showing the testing device applied to an internal combustion motor. Fig. 2 is an enlarged detail view of the testing device, with parts broken away and in section to more clearly illustrate the interior 25 construction of the device. Fig. 3 is a detail sectional view on the line 3—3 of Fig. 2, with some of the parts shown in elevation.

Like reference characters indicate corresponding parts throughout the several views.

30 5 indicates a current conducting member adapted to be grounded on the motor. As here shown it consists of a hollow weight electrically and mechanically connected to a flexible current conducting member 6, the 35 free end of which is adapted to be placed in circuit with the spark plug of an internal combustion motor. In the preferred form I provide a plurality of flexible current conducting members 6, which may conveniently 40 be made in one piece and bent into a loop as at 7, and a portion of the insulation removed and the loop inserted in the hollow portion of the weighted member 5. A body of current conducting material 8, such as lead or 45 Babbitt metal, surrounds the looped end of the flexible current conducting member and forms an electrical connection between the latter and the weight. A body of fiber 9 may also be inserted in the opening in the 50 said weight to prevent the insulation surrounding the flexible current conducting members from being cut or injured. Preferably the said flexible current conducting members 6 are mechanically and electrically 55 connected, as shown, to the contacts 10, in this case by passing up through an opening 11 in the side of the said contact member

and having the insulation removed so that the naked wire 12 will extend into the tips 13 of the said contact members. The contact 60 members are formed with a hollow space 14 adjacent to the said tips, into which the insulated part of the current conducting members may extend, and insulated handles 15 are preferably utilized for carrying the con- 65 tact members.

In Fig. 1 the method of using the device is shown and for this purpose there are disclosed the electrical circuits generally utilized in connection with the sparking device 70 of the ignition system of an internal combustion motor. Ordinarily the path of the secondary or ignition current is from the contacts 16 of the distributor, through secondary wires 17, each going to one of the 75 spark plugs 18, 19, 20 and 21. Thence the circuit is across the spark plug gap in a well-known manner, through cylinders and ground wire, indicated in dotted lines 22, to the rotor 23 of the magneto. 80

In using the testing device of the present invention the weighted member 5 is placed on the motor frame, as shown, and thus a ground connection is made from the same to the rotor of the magneto. Then by placing 85 the contact member 10 on one of the spark plugs the current will be shunted from the secondary wire 17 to the said contact member 10, thence through the flexible current conducting member 6 and to the weighted 90 current conducting member 5. Thus the current is prevented from passing through the spark plug inside the cylinder.

In the diagram shown in Fig. 1 both of the contacts 10 are utilized, one being placed 95 on the spark plug of the first cylinder and the other on the spark plug of the third cylinder. Assuming the motor to be running, then if the second and the fourth cylinders are firing regularly, it is obvious that the 100 misfiring, due to faulty compression or other causes, is in either the first or the third cylinder. By changing the contact member 10 of the testing device from the third cylinder to the fourth cylinder, it will be ascertained 105 whether or not it is the first or the third cylinder which is misfiring, because if the second and the third cylinders fire regularly, it is clear that it must be the first cylinder which is misfiring. This is one method out 110 of several whereby this device can be utilized, since of course the cylinders may be tested in any combination desired.

In addition, by placing the weighted mem-

ber 5 on the frame of the motor and by holding one of the terminals about one-eighth of an inch from the top of the spark plug, a spark can be produced between the top of the spark plug and the contact member 10. In this way it can be determined whether or not current is passing properly from the distributor of the magneto. If the spark device is of the make and break type, the contact member 10 can be placed in contact with one of the spark plugs and then moved slowly out of contact therewith, whereby a spark will likewise be produced.

At the end of one of the contacts 15 I may pivot two gages, one, 24, for gaging the proper distance between the two points of the spark plug inside the cylinder, when using the magneto, and the other, 25, for gaging the proper distance between the same points when using the battery. The end of the other handle 15 may be provided with a fork 26 by means of which the spark plug points can be readily bent or adjusted. If desired, more than two contact members 10 may be employed.

What is claimed, is:

1. A testing device for internal combustion motors comprising, a current conducting member adapted to be grounded on the motor, a plurality of handles each having a contact member adapted to be placed in circuit with a spark plug, and flexible current conducting members connected to the first-mentioned current conducting member and to the respective handles.

2. A testing device for internal combustion motors comprising, a plurality of handles each having a contact member adapted to be placed in circuit with the spark plug, a flexible current conducting member connected to each contact member, and a common current conducting member connected to the flexible current conducting members and adapted to be grounded on the motor.

3. A testing device for internal combustion motors comprising, a current conducting member adapted to be grounded on the motor, and a flexible current conducting member formed into a loop and having its said loop electrically and mechanically connected to the current conducting member, the free ends of said flexible current conducting member being adapted to be placed in circuit with the spark plug.

4. A testing device for internal combustion motors comprising, a current conducting member adapted to be grounded on the motor, a flexible current conducting member formed into a loop and having its said loop electrically and mechanically connected to the current conducting member, and handles having contact members adapted to be

placed in circuit with the spark plugs electrically and mechanically connected to the free ends of the flexible current conducting member.

5. A testing device for internal combustion motors comprising, a weighted current conducting member adapted to be grounded on the motor, a plurality of handles each having a contact member adapted to be placed in circuit with the spark plug, and flexible current conducting members connected to the weighted current conducting member and to the respective handles.

6. A testing device for internal combustion motors comprising, two handles each having a contact member adapted to be placed in circuit with the spark plug, a flexible current conducting member connected to each contact member, and a weighted common current conducting member connected to the flexible current conducting members and adapted to be grounded on the motor.

7. A testing device for internal combustion motors comprising, a weighted current conducting member adapted to be grounded on the motor, and a flexible current conducting member formed into a loop and having its said loop electrically and mechanically connected to the weighted current conducting member, the free ends of said flexible current conducting member being adapted to be placed in circuit with the spark plug.

8. A testing device for internal combustion motors comprising, a weighted current conducting member adapted to be grounded on the motor, a flexible current conducting member formed into a loop and having its said loop electrically and mechanically connected to the weighted current conducting member, and handles having contact members adapted to be placed in circuit with the spark plugs electrically and mechanically connected to the free ends of the flexible current conducting member.

9. A testing device for internal combustion motors comprising, a flexible current conducting member adapted to be grounded on the motor, a contact member having an opening in its side through which said flexible current conducting member may extend, and means for electrically and mechanically connecting the flexible current conducting member and the contact member.

Signed at Plainfield in the county of Union and State of New Jersey this 21 day of April A. D. 1913.

WILLIAM CUTTER FORCE.
